UNITED STATES PATENT OFFICE.

GEORGE H. AYLWORTH, OF BRIGHTON, ILLINOIS.

GATE.

SPECIFICATION forming part of Letters Patent No. 444,325, dated January 6, 1891.

Application filed July 18, 1890. Serial No. 359,154. (No model.)

To all whom it may concern:

Be it known that I, GEORGE H. AYLWORTH, of Brighton, in the county of Macoupin and State of Illinois, have invented a certain new and useful Improvement in Gates, of which the following is a full, clear, and exact description, reference being had to the accompanying drawings, forming a part of this specification.

10 This may be regarded as in some respects an improvement upon the device patented to me June 12, 1888, and numbered 384,552, the gate being opened and closed by ropes extending along the side of the road a short distance in both directions, and the cord acting to disengage the latch before any strain comes upon the gate to swing it on its hinges.

15 My present improvement applies partly to a device to avoid the moving of the cord which 20 at the time may be inactive and partly to the form of the latching device, the novelties being set forth in the claims.

Figure I is a perspective view of the improvement. Fig. II is an enlarged vertical 25 section at II II, Fig. III. Fig. III is a detail side view of the latching device with the cords removed. Fig. IV is a vertical transverse section at IV IV, Fig. III. Fig. V is an enlarged vertical section at V V, Fig. I.

30 1 is the hinge-post, and 2 the latch-post, of the gate.

4 are the hinges connecting the gate to the post 1.

5 is a latch pivoted at the inner end 6 to 35 the gate and extending through a vertical slot in the end piece 7.

8 is the catch, secured to the latch-post 2 and having a central recess 9 to receive the end 10 of the latch. On each side of the recess are inclines 11, up which the end of the 40 latch may slide.

12 is a sliding and swinging stop-piece, which passes through a slot 13 in the bracket 14, which is secured to the latch-post. The piece 12 widens at the lower end 15 and has at the upper end a head 16, which normally rests upon the top of the bracket, so that the piece 12 hangs in a vertical position and its lower end closes the top of the recess 9, as seen in broken lines in 45 Fig. II. This is the position it occupies when the gate is closed. As the gate is closing, the latch hits the stop-piece 12 and carries it with it

into the position shown in full lines in Fig. II, which is as far as it can be forced from the vertical position, as the sides of the stop-piece 55 12 then bear against the ends of the slot 13, so that the gate cannot swing from one side to the other past the catch, but is arrested each time by the stop 12. The latch is arrested in proper position to fall into the recess 9, which it does as soon as the cord is released. As soon as the end of the latch falls into the recess 9 the stop-piece regains its vertical position, as seen in broken lines in Fig. II. When the latch is lifted by the cord, it 60 65 carries up the stop-piece with it and is free to escape either way, according as the gate is opened to one side or the other.

17 is a grooved pulley, which turns freely on the latch, and which acts as a weight to 70 depress the free end of the latch when released from the upward pull of the cord. The two cords 18 and 19 are similar in all respects, one of them acting to throw the gate in one direction and the other in the other 75 direction. A description of one cord will apply equally to the other, except as to the described opposite action on the gate. One end 20 of each cord is fixed to the lower side of the pulley-weight 17 when it is in its normal position, (see Fig. IV,) so that on the pulling of either cord the pulley will turn to the right or the left, as the case may be. Suppose the cord 18 to be pulled, the pulley would turn in the direction indicated by the arrow, Fig. IV, 80 85 and the cord 19 would be coiled upon the pulley as the cord 18 uncoiled from it. It will be seen that the position of the cord 19, except for that part of it coiled upon the pulley, would be unchanged and that the pulley 90 would ascend half the distance that the cord 18 ascended. The cords extend upward from the pulley and pass over pulleys 21, and from the pulleys 21 through the eye 22 of a post 23, fixed to the top rail 24 of the gate. 95

26 is a lever whose front end is strapped to the post 23 so as to turn freely on the post. The lever passes through a swivel-eye 27, having bearing at the top of the hinge-post 1. This swivel-eye forms the fulcrum of the lever. From the eye 22 the cords pass to and through an eye 28 at the end of the lever 26, from which point the cords separate, extending along the side of the road in opposite di-

rections. Each cord extends from the eye 28 to a pulley 29 upon a post 30. The post has a hollow case 31, containing a weight 32, to which is fixed the housing 33 of two grooved 5 pulleys 34.

At 35 are grooved pulleys turning in bearings fixed to the side of the post 30. The cord extends from the pulley 29 over one of the pulleys 35, then beneath one of the pulleys 34, then over the other pulley 35 and beneath the other pulley 34, and then up to a point 36 on the post 30, to which the end of the cord is fixed.

37 are posts having catches 38, upon which 15 the latch 5 engages when the gate is swung open.

The operation of the device is as follows: Suppose a person to pull the cord 18, for this purpose taking hold of the part of the cord between pulleys 29 and 35. The latch 5 will first be lifted, carrying up with it the stop-piece 12. As soon as the latch attains its upper position the cord acts on the lever 26 and draws its rear end (at 28) toward the pulley 29, (of the cord 18.) The end 10 of the latch 5 passes from beneath the stop-piece 12 and the gate swings open away from the person who is pulling the cord. The latch engages in the catch 38 and the gate remains open until the cord 19 is pulled, which lifts the latch 5 from the catch 38 and swings the gate shut, the latch hitting the stop-piece 12 and the movement of the gate being arrested with the latch over the recess 9, into which the end of the latch drops. As soon as the person leaves hold of the cord the slack of the cord is taken up by the weight 32, but never with force enough to lift the latch 5. It will be understood that when either of the cords (18 or 19) is drawn while 40 the latch is ascending, the other cord will be at perfect rest, except that part of it which is wound upon the pulley 17, and that when the pulley has been turned one-half of a revolution the latch will be above the recess 9 of 45 the catch and will have reached its upper position, so that there will be no endwise movement of the inactive cord. As the gate swings open the inactive cord will be drawn outward from the case 31, and when the latch has reached 50 the post 37 the active cord is released and the

latch drops into the catch 38. The descent of the latch takes place without any end movement of the inactive cord, for it will be seen that the only part of the cords drawn endwise by the latch in descending is that part of the active cord between the hand of the operator and the latch. This is a very important feature, because the cord being in the open air is liable to be rendered rigid by moisture, and thus the weight of the pulley and the latch, which might be ample to draw down one cord, might be inadequate to draw down the other cord at the same time. There is a practical advantage in widening the lower end 15 of the stop-piece 12, because, as a result, the edge against which the latch strikes on the closing of the gate is perpendicular, and so does not force the free end of the gate downward, as would be the case if the width were not increased at the lower end. This is illustrated in Fig. II. If the latch should strike against a surface so inclined as to force the latch downward, it would cause the sagging of the free end of the gate—an injury to which gates are very liable.

I claim as new and of my invention—

1. The combination, with a gate-latch, of two latch-lifting cords, as 18 19, and a weight-pulley 17, turning freely on the latch, to which the ends of both cords are attached, substantially as and for the purpose set forth.

2. The combination, in a gate, of the latch 5, a weight-pulley 17, turning freely thereon, and two lifting-cords attached to the lower part of the pulley at one end and connected with a weight 32 at the other end, substantially as and for the purpose set forth.

3. The combination, with a gate-latch and a catch 8, provided with a recess 9, of the swinging stop-piece 12, formed with a flared lower end 15, having straight side edges, and a support for the stop-piece, in which it has limited movement to bring either of its side edges in perpendicular fixed position over the opposite side of the recess from which the lower end is moved, substantially as described.

GEORGE H. AYLWORTH.
